CHARGE FORMING DEVICE

Frank C. Mock, South Bend, Ind., assignor to
 Bendix Aviation Corporation, South Bend, Ind.,
 a corporation of Delaware

Application August 3, 1940, Serial No. 350,517

23 Claims. (Cl. 261—23)

This invention relates to charge forming devices, primarily of the pressure feed or injection carburetor types, and is particularly concerned with the provision of fuel discharge nozzle arrangements which are adapted to disperse and distribute the fuel through the air flowing through the induction passage.

With the continuous development of larger and larger internal combustion engines, particularly for aircraft use, the problem of obtaining uniform distribution of fuel and air to the individual cylinders of the engine has grown increasingly difficult. For aircraft use it has been found desirable to use a carburetor of the pressure fuel or injection type in which the fuel is maintained under superatmospheric pressure to decrease the tendency of the fuel to boil prior to its delivery into the engine manifold; and furthermore, to inject the fuel into the manifold posterior to the engine throttle to prevent throttle icing. Both of these arrangements aggravate the problem of distribution and dispersion of the fuel, the first tending to result in the delivery of a solid stream of fuel to the air stream and the latter eliminating the fuel break-up effect which is normally experienced in a posterior throttle carburetor as the fuel passes the throttle valve. Furthermore, the increased engine size has resulted in larger induction passages to accommodate the larger quantities of fuel mixture now required. To obtain uniform distribution of fuel through an induction passage having a large cross-sectional area is obviously more difficult than with one of small cross-sectional area.

In addition, engines often have peculiar distribution characteristics resulting from valve timing, manifold characteristics, and other design variables which result in uneven fuel distribution to the individual cylinders even though the carburetor creates a condition of uniform distribution at the point of fuel delivery to the manifold. Under such conditions it is desirable that the carburetor be able to deliver the fuel in a non-uniform manner to offset the other effects so that the mixture received by the individual cylinders is of a uniform richness.

It is accordingly an object of my invention to provide a means whereby the fuel delivered to the air stream may be so distributed that the individual cylinders receive mixture of a uniform richness.

Another object of the invention is to secure uniform fuel distribution to the individual cylinders with relatively simple devices of high efficiency and consistent performance.

Another object is to produce fuel discharge nozzle arrangements whereby the carburetor fuel distribution pattern may be readily varied or controlled.

Still another object is the provision of improved fuel discharge nozzle arrangements for charge forming devices.

The invention possesses many other objects and advantages which will become apparent to one skilled in the art from the following description and appended drawings in which:

Figure 1 is an elevational view partially in section of a charge forming device embodying the invention, the portion in section being taken on the line 1—1 of Figure 2;

Figure 2 is a bottom view of the charge forming device of Figure 1;

Figure 3 is a sectional view taken on the line 3—3 of Figure 2;

Figure 4 is a bottom view of a charge forming device embodying another modification of the invention, a portion of the fuel tube being broken away;

Figure 5 is a partial view in section taken on the line 5—5 of Figure 4;

Figure 11 is a bottom view of the adapter of Figure 10;

Figure 12 is a sectional view taken on the line 12—12 of Figure 11; and

Figure 13 is a sectional view taken on the line 13—13 of Figure 11.

With particular reference to Figure 1, there is disclosed a charge forming device of the pressure feed type, such as is more particularly described in my copending application Serial No. 202,206, filed April 15, 1938, having an air inlet or scoop section 10, a body section 12, a nozzle adapter section 14 and a fuel regulator indicated generally at 16. The main body section includes a pair of air passages or barrels 17 and 18, each of which contains a large venturi 20, a primary venturi 22 and a throttle 24. An annu-

lulus 26 is provided in the small venturi 22 and communicates with the regulator 16 by passages not shown. Tubes 28 in the venturi 26 are subjected to air entrance pressure and also communicate with the regulator 16. The Venturi suction and air scoop pressure are utilized in the regulator to control the quantity of fuel delivered to the conduit 30, leading to the adapter section 14, as is particularly described in the above copending application. Passages 31 and 32 connect the Venturi annulus 26 with a chamber 33 (Figure 3) within a nozzle cap 34. A conduit 35 connects the air inlet 10 with a passage 36 in the adapter section 14, transmitting air thereto for reasons which appear hereinafter.

The adapter 14 is preferably formed with the separate barrels 17 and 18 extending therethrough although it may have a single elongated passage if desired. The material between the barrels is milled out as indicated at 38 and 39 to respectively receive the nozzle cap 34 and the lower portion of the discharge nozzle assembly indicated generally at 40. The adapter section is adapted to be attached by means of the flange 42 to an engine intake manifold generally having a single elongated opening into which the barrels 17 and 18 discharge.

The portion 44, Figure 3, between the barrels of the adapter is bored to receive a valve body 45 having a valve seat 46, and forms therewith an annular chamber 47 which receives fuel from the conduit 39 through a passage 48 and delivers it to the interior of the body 45 through ports 49. The body 45 slidably receives a valve 50 of flat-sided stock having a tapered portion 51 adapted to cooperate with the seat 46. A diaphragm 52 is secured at its central portion to the valve 50 and is clamped at its outer edge between the cap 34 and the body 45, the parts being secured to the adapter by cap screws 54 to form a fluid-tight assembly. A compression spring 56 urges the valve 50 against the seat 46.

A substantially X-shaped member 60 is bored to receive a nozzle cylinder 62 and forms therewith an annular chamber 63 which communicates through passage 64 with the passage 36 leading to the air inlet. Cap screws 66 secure the member 60 and cylinder 62 to the adapter portion 44, gasket 67 and packing 68 being provided to maintain the assembly fluid tight. A piston 70 is slidably received in the cylinder 62 and is urged against a shoulder therein by a compression spring 71 acting between the piston and a cap 72 threaded into the end of the cylinder 62.

The member 60 has four arms 74, 75, 76, 77 which extend transversely of the induction passage and are curved in the longitudinal plane of the induction passage, from base to tip, in the direction of air flow, as best shown in Figure 3, and are also curved in the transverse plane of the induction passage as best shown in Figure 2. The arms have a cross-sectional contour as indicated in the revolved section at 78 of Figure 3. The relatively flat leeward surfaces of the arms shield the region in the immediate lee of the arms from direct air currents.

Fuel discharge orifices 80 are provided in the cylinder 62 above the shoulder against which piston 70 seats and are positioned in the immediate lee of each of the arms of the X member and are adapted to discharge jets of fuel longitudinally of and in the lee of the arms. Fuel orifices 82 of larger diameter than orifices 80 are similarly positioned with respect to the arms but are located below the shoulder to be gradually

uncovered by the piston as the quantity of fuel discharged increases.

During operation at idle or at low fuel flow, fuel under pressure is delivered by the regulator 16 to the interior of nozzle body 45 through the conduit 30, passage 48, annulus 47 and ports 49. The pressure of the fuel within the nozzle body acts on diaphragm 52 and urges it upwardly to open the valve 51 in opposition to the spring 56. Since the diaphragm area is relatively large compared with the area of valve seat 46, the valve 51 maintains the fuel anterior to the seat at a predetermined and substantially constant pressure unless modified by means hereinafter described. Fuel under pressure therefore passes the seat 46 into the cylinder 62 and discharges through orifices 80 in the lee of the arms of the X member, the arms shielding the jet of fuel from direct air currents and allowing it to carry transversely in the induction passage.

As the fuel flow increases, the fuel pressure acting on the piston 70 increases and urges it downward against the spring 71 to uncover the discharge orifices 82, thus providing additional area for the discharge of fuel. This arrangement results in a forceful ejection of fuel at low flows, in contrast to the dribbling of fuel which would occur if large discharge orifices were used, without requiring an excessive pressure at high fuel flow as would be necessary if small discharge holes were used.

The chamber 33 in nozzle cap 34 may be vented through passage 32 to the atmosphere or if desired to the Venturi annulus 26 through passage 31, as shown in Figure 1. If vented to atmosphere the valve 50 and diaphragm 52 maintain the fuel anterior to the seat 46 at a predetermined and substantially constant pressure. With the arrangement shown, Venturi suction is transmitted to chamber 33 and acts on diaphragm 52 to assist the fuel pressure in opening valve 51. As the Venturi suction increases with increase in air flow, less fuel pressure is required to open the valve. Thus the fuel pressure required to open valve 51 decreases as the quantity of fuel increases.

At idle or operation at small throttle openings there is very little air flow through the passage and if it were not for the curvature of the arms of the X member in the longitudinal plane the fuel discharged from orifices 80, being shielded from direct air current by the arms, would carry substantially across the induction passage and deliver too great a portion of the fuel to the outer periphery of the barrels. Due to this curvature of the arms, the fuel jet impinges against the leeward surfaces thereof and is broken up into smaller particles, a portion of which will be carried away by the air stream. The balance of the fuel, due to its inertia, flows along the leeward side of the bar and is carried off of the edges of the bar throughout its full length by air currents which will be presently described. By controlling the curvature of the arm the fuel may be made to impinge against the arm at a point spaced any desired distance from the center or body portion of the X member, thus preventing too great a portion of the fuel from carrying to the outer periphery of the barrel. To further assist breaking up the fuel at low rates of air flow, air discharge orifices 84 are provided which receive air from the air inlet through conduit 35, passages 36, 64 and annulus 63 and direct it across the path of the fuel discharged from orifices 80.

The arms of the X member protrude into the air stream of the induction passage and because they are flat on the lee side cause a region of backwash or retrograde currents in the lee of the arms. This region of low velocity air is a high pressure region and air moves continuously from the center of this region to the high velocity, low pressure regions at the edges of the arms. In this manner a continuous movement of air is produced which carries with it fuel delivered into the shielded region. The arms, however, shield the fuel from direct air currents and allow it to carry transversely of the induction passage and be delivered into the air stream over the full length of the arm. By controlling the width of the flat leeward surfaces the amount of retrograde currents, which accomplish the tearing away of fuel from the bar, may be controlled.

The same movements of air occur at the portions of the arms which are inclined from a transverse plane of the induction passage. However, when the retrograde currents reach the edge of the arms, they are not swept away by stream flow which is at right angles to the member, but rather by stream flow which has a substantial component in the direction of the arm. The lee currents thus tend to carry along the member and carry the fuel with it. Due to these effects fuel ejected upon the inclined portions of the arm is carried along the bar and is taken off as it progresses, thus resulting in a delivery of fuel to the air stream along all of the edges of the arms of the X member.

Thus the width of the arm at its various sections, the contour of the arm in the longitudinal plane, and the size and direction of the air orifices may be varied to give any desired characteristic of fuel distribution to the air stream along the length of the arm. Furthermore, by varying the curvature of the arms in the transverse plane, as shown in Figure 2, the distribution of fuel to the induction passage may be further controlled. Thus by controlling these variables the distribution characteristics of the carburetor may be adjusted or varied to compensate for other distribution peculiarities of the engine to thereby accomplish uniform distribution to the individual engine cylinders.

The "rake" type of fuel discharge bar shown in Figures 4, 5, 6 and 7 operates on substantially the same principle as the X type of jet. The rake is comprised of a central body 86 which is adapted to be bolted to the adapter portion 44, as shown in Figures 4 and 5, and has tubes 87 and 88 secured therein which project transversely into the induction passage. The tops or leading surfaces of the tubes are flattened, as shown in Figure 6, and have flat plates 89, 90 soldered or welded thereto. The plates have a plurality of finger-like projections 92 extending transversely of the induction passage and at substantially right angles to the tubes. Fuel discharge orifices 94 are provided in the tube in the immediate lee of each finger-like projection and discharge jets of fuel transversely of the induction passage. The orifices 94, as shown in Figures 5 and 6, preferably communicate with the interior of the tube 88 adjacent its uppermost portion so that vapor will be drawn through orifices 94 as it forms, rather than after it has collected in large bubbles. The finger-like projections may be bent in the direction of air flow whereby the fuel will impinge against the leeward sides thereof, and/or may be formed integrally with the tubes, as by casting, as shown in Figure 7.

The operation is much like that of the X bar. The relatively quiet air under the finger-like projections 92 allows the discharged fuel to travel substantially the length of the projections. Air currents which swirl from the center of the lee area to the edges of the members carry with them portions of the fuel and deliver it to the main air stream.

10 The rake may be readily adapted for use in induction passages of any shape by varying the lengths and widths of the projections 92 as well as the length and shape of the tubes. These variables, together with the size of the individual fuel orifices, may be adjusted to give any desired fuel distribution pattern, thus compensating for any distribution peculiarities of the engine or its induction passage.

15 In Figure 8, the nozzle adapter section 110 is of the elbow type having an elongated cross-section at its upper vertical flange 112 which is adapted to receive a twin barrel body 114 of a charge forming device. The cross-section of the adapter progressively changes from an elongated section at the vertical flange to a circular section at the lower horizontal flange 115, the latter being adapted to be connected to the intake manifold of an engine. A web 116 is cast in the adapter and contains a bore 118 therethrough having enlarged upper and lower portions 119 and 120. A fuel 20 control valve assembly is secured to the adapter 110 by means of bolts 122 and comprises a nozzle body 124 having a shouldered aperture therethrough in which a long sleeve 126 is secured by means of nut 127 and packing 128. A long valve 25 member consisting of a lower tapered portion 130, a tube 131, and an upper member 132, cooperates with a seat 134 in the lower end of the sleeve 126. The valve is connected at its upper end to a diaphragm as in the previous modifications, the 30 chamber above the diaphragm being vented either to atmosphere or Venturi section. The lower and upper portions 130 and 132 of the valve member have enlarged fluted sections 136 and 137 to guide the valve in the sleeve 126.

35 40 45 A fuel discharge member 140 having four prong or finger-like extensions 142 is secured to the lower surface of the web 116 by bolts 144. The extensions 142 have flat leeward surfaces and a cross-sectional contour as indicated in the re-50 volved section at 145 of Figure 9. A central chamber 146 in the member 140 slidably receives the end of sleeve 126, forming a fluid-tight connection therewith by means of the packing 148. Fuel discharge tubes 150 are provided in the lee of each 55 extension 142 and communicate with the chamber 146. The tubes may be directed parallel to the extensions if desired, or at an angle toward the extensions whereby the fuel discharged will impinge against the flat leeward surfaces, or even 60 at an angle away from the extensions. An annular chamber 152 is provided in the member 140 which receives air from the air inlet through a conduit 154, passage 155, an annular chamber 156 between the sleeve 126 and the walls of bore 65 118, and enlarged chamber 120 and discharges it through air discharge orifices 158 across the tips of the tubes 150.

70 During operation, fuel is received from the regulator through passage 160 and passes downwardly within the sleeve 126, past the fluted sections 137, 138, past the seat 134 and into the chamber 146 from where it is discharged through tubes 150 in the lee of the projections 142. Air from the air inlet or from any other source of air at a pressure greater than the pressure in the induction

passage flows through the annular chamber 156 surrounding the fuel conducting sleeve 126 and discharges through the orifices 158. The flow of air over the sleeve 126 cools the fuel flowing therethrough and tends to prevent boiling of the fuel prior to its discharge into the induction passage. The flat-sided projections 142 shield the fuel discharged by the tubes from direct air currents and create retrograde currents which will deliver the fuel to the air stream over the full length of the projections, as has been previously explained.

The adapter section 210 of Figure 10 is adapted to be connected to a twin barrel main body 212 and deliver into an induction passage having a single elongated passage. The fuel discharge bar comprises a central body portion 214 having two laterally extending bars 215, 216 formed integral therewith and is secured to the side wall of the adapter. The bars 215, 216 are of a streamlined shape, as indicated in Figure 13, but have lateral projections 217 at spaced distances along the bars of a contour best shown in Figure 12. The finger-like extensions 218, 219 of the projections 217 have flat leeward surfaces 220, 221. A fuel control valve assembly comprising a cap 222, a body 224 having a sleeve-like extension 226 including a valve seat 228, and a valve stem assembly indicated generally at 230 is connected to the adapter by bolts 232 which extend through the wall of the adapter and are threaded into bosses 234 of the discharge bar body. The sleeve 226 is received within the body portion 214 and forms a fluid-tight connection with a cup-like member 236 by means of packing 238. Small ports 240, 241 and a large port 242 are provided in the cup-like member 236 and communicate with a fuel passage 244 extending longitudinally within the bars 215, 216. A piston 246 within the cup member 236 is spring urged to the right and closes port 242 at low rates of fuel flow but uncovers it as the fuel flow increases.

As shown in Figure 12, a vertical passage 250 is provided in each of the projections 217 which communicates with the fuel passage 244 and is plugged at its lower end. Inclined passages 252 intersect the passage 250 and have tube-like projections 254 which discharge fuel in the lee of the flat surfaces 220, 221. Air discharge passages 256 are provided in each of the projections 217 to direct a jet of air across the path of the fuel discharged by the tubes 254. The passages 256 communicate with an air passage 258 extending longitudinally within the bars 215, 216. The passage 258 receives air through passage 260, annular chamber 262 surrounding the sleeve 226, and a conduit 264 leading to the air inlet or to any other source of air having a pressure greater than that within the induction passage. The air flow through the chamber 262 thus cools the fuel flowing through the sleeve 226, as was described in connection with Figure 8.

During operation fuel is received from the regulator through conduit 270 and passes through the sleeve 226, past the valve seat 228, through ports 240, 241 and 242, into the passage 244, into passages 250 and discharges through passages 252 and tubes 254 in the lee of the finger-like extensions 218, 219. As previously explained, the flat surfaces 220, 221 shield the fuel from direct air currents and create retrograde currents which will deliver the fuel to the air stream along the full length of the projections 218, 219. By varying the lengths of the finger-like projections 218, 219, the size and direction of the discharge tubes 254,

the spacing of the projections 217 along the bars 215, 216, and the size and direction of the air discharge jets 256, any desired distribution pattern may be obtained.

5 Although the invention has been described with reference to several particular embodiments, it will be readily apparent that various features of the several embodiments may be combined or changes made in the form and arrangement of the parts without departing from the spirit of the invention. It is not intended that the scope of the invention shall be limited to the forms shown or otherwise than by the terms of the appended claims.

15 I claim:

1. In a charge forming device, an induction passage, a throttle in said passage, a plurality of members having substantially flat leeward surfaces extending transversely within the passage 20 posterior to the throttle and terminating at points spaced from the wall of the induction passage, fuel orifices adapted to discharge jets of fuel transversely of the induction passage in the immediate lee of said members and in a direction along and generally toward the ends of said members, a fuel conduit for supplying fuel to said orifices, and a valve responsive to fuel pressure for controlling said conduit.

2. In a charge forming device, an induction 30 passage, a throttle in the passage, a member positioned posterior to the throttle and having a plurality of projections extending transversely of the induction passage, said projections having substantially flat leeward surfaces to form 35 regions protected from direct air currents, fuel discharge orifices positioned in the lee of said projections and adapted to discharge jets of fuel into said region transversely of the passage in a direction along the members whereby it will carry 40 across the induction passage, means to supply fuel to said orifices, air discharge orifices adjacent the fuel discharge orifices positioned to discharge jets of air in a direction to intersect the path of the fuel discharged by the fuel orifices, and means for supplying air to said air discharge orifices.

3. In a charge forming device, a body having 45 an induction passage therethrough, a support on the body, a plurality of members extending transversely of the induction passage connected to said support and terminating at points spaced from the induction passage wall, fuel discharge orifices adjacent said support and positioned to 50 discharge fuel in jets transversely of the induction passage in the immediate lee of said members along lines intersecting the leeward surfaces of said members, a conduit for supplying fuel to said orifices, and a spring loaded valve adapted to open in response to fuel pressure for controlling said conduit.

4. In a charge forming device, body means 55 having an induction passage therethrough, a throttle in the passage, a member mounted on said body means and having a plurality of finger-like projections extending therefrom transversely of and only partially across said induction passage, said projections having substantially flat leeward surfaces, fuel discharge orifices adapted to discharge jets of fuel transversely of the induction passage in the immediate lee of said projections, means to supply fuel under positive pressure to said orifices, air discharge nozzles positioned to discharge jets of air which 60 intersect the path of the fuel discharged by the

said fuel discharge orifices, and means for supplying air to said air discharge nozzles.

5. In a charge forming device, an induction passage, a support, a plurality of members extending from the support transversely of and only partially across the induction passage and being inclined from support to tip in the direction of air flow, said members having substantially flat leeward sides, and orifice means adjacent the support adapted to discharge jets of fuel transversely of the induction passage in the lee of said members along lines which intersect the leeward sides of the members.

6. In a charge forming device, means defining an induction passage, a throttle therein, a substantially X-shaped member supported in the induction passage posterior to the throttle and having its arms projecting transversely of the passage, a fuel nozzle comprising a body adjacent the central portion of the X member and posterior thereto, fuel discharge orifices in said body adapted to discharge jets of fuel transversely of the induction passage in the immediate lee of said arms, a fuel conduit for conducting fuel to said nozzle body, and a spring loaded piston in said body adapted to uncover said orifices in response to fuel pressure.

7. In a charge forming device, an induction passage having an air inlet, a throttle in the passage, a member having a plurality of fingers extending transversely in said induction passage posterior to the throttle, fuel discharge nozzles adjacent the base of and in the lee of said fingers adapted to deliver jets of fuel transversely of the passage in the lee of said fingers, a fuel conduit for supplying fuel to said nozzles, air discharge jets adapted to discharge air along a path intersecting the path of the jets of fuel discharged by said fuel nozzles, and a duct connecting said air jets with the air inlet.

8. In a charge forming device, an induction passage, a bar extending substantially across said induction passage and having a plurality of lateral projections therefrom extending transversely of the induction passage, said projections having relatively flat leeward surfaces, a fuel conduit in said bar, a fuel orifice in said bar at the base of each projection and adapted to receive fuel from said conduit and adapted to discharge a jet of fuel transversely of the induction passage in the lee of said projection and toward the tip thereof, and means for supplying fuel to said conduit.

9. In a charge forming device having an induction passage and a throttle therein, a bar extending substantially across said passage posterior to the throttle and having a plurality of lateral projections therefrom extending transversely of the passage and terminating at points spaced from the wall of the induction passage, a fuel conduit in said bar, a fuel nozzle at the base of each projection adapted to receive fuel from said conduit and adapted to discharge a jet of fuel transversely of the passage in the lee of said projection and toward the tip thereof, and means for supplying fuel to said conduit.

10. The invention defined in claim 9 comprising in addition an air passage in said bar, a duct communicating said air passage with a source of air at substantially atmospheric pressure, and air discharge nozzles adapted to receive air from said air passage and adapted to discharge jets of air along lines intersecting the paths of the jets of fuel discharged by said fuel nozzles.

11. In a charge forming device, an induction

passage, a bar extending transversely of the induction passage, a support extending inwardly from the wall of the passage and connected to said bar, a fuel duct in said bar extending substantially the full length thereof, a fuel conduit leading from a source of fuel to said duct, lateral projections from said bar extending transversely of the induction passage, fuel orifices in said bar adapted to receive fuel from the duct and discharge jets of fuel in the lee of said projections, an air duct in said bar having air discharge orifices adapted to discharge jets of air in intersecting relation with the jets of fuel, and an air supply passage communicating with said air duct and surrounding a portion of the fuel conduit whereby air flow therethrough will cool the fuel flowing through the fuel conduit.

12. In a charge forming device, an induction passage, a plurality of members within the passage and extending transversely and longitudinally thereof, a group of fuel discharge orifices positioned to discharge fuel transversely of the induction passage in the immediate lee of said members, a second group of fuel discharge orifices longitudinally spaced in the induction passage from the first mentioned group and similarly positioned with respect to the members, a fuel conduit for supplying fuel to said orifices, and a spring loaded valve responsive to fuel pressure controlling one of said groups of fuel discharge orifices.

13. In a charge forming device, an induction passage, a plurality of members within the passage and extending transversely thereof, a group of fuel discharge orifices positioned to discharge fuel transversely of the induction passage in the immediate lee of said members, a second group of fuel discharge orifices longitudinally spaced in the induction passage from the first mentioned group and similarly positioned with respect to the members, a spring loaded valve responsive to fuel pressure controlling the flow of fuel to at least one of said groups of fuel discharge orifices, a group of air discharge orifices directed to discharge air across the path of fuel discharged by the fuel orifices, means for supplying fuel to the fuel orifices, and means for supplying air to the air orifices.

14. In a charge forming device, spaced parallel induction passages, means forming a support between the passages, a multi-armed member secured to said support and having its arms extending transversely within the passages, a group of fuel discharge orifices positioned to discharge fuel transversely of the induction passages in the immediate lee of said arms, a second group of fuel discharge orifices longitudinally spaced in the induction passage from the first mentioned group and similarly positioned with respect to the members, a fuel conduit for supplying fuel to said orifices, and a spring loaded valve responsive to fuel pressure controlling the flow of fuel to at least one of said groups of fuel discharge orifices.

15. In a charge forming device, spaced induction passages, a wall separating the passages and forming a support, a multi-armed member secured to the support and having its arms extending transversely within the passages, the leeward surfaces of said arms being relatively flat, fuel discharge orifices adapted to discharge jets of fuel transversely of the induction passages in the immediate lee of the arms and toward the ends of the arms, a fuel conduit supplying fuel to the fuel discharge orifices, and a fuel pres-

sure responsive valve controlling the fuel conduit.

16. In a charge forming device, a pair of spaced parallel induction passages, a support positioned between and adjacent said passages, an element mounted on said support having portions extending into the said passages, said portions including a plurality of members extending transversely of the passages and having relatively flat leeward surfaces, said members terminating at points spaced from the walls of the induction passages, fuel orifices for discharging jets of fuel transversely of the induction passages in the immediate lee of said members in a direction along and generally toward the tips of said members, and a fuel conduit in the support adapted to receive fuel from a source and to supply fuel to said fuel orifices.

17. In a charge forming device, means defining spaced parallel induction passages, means separating said passages and forming a support, a member secured to the support and having a plurality of projections extending transversely within the passages and terminating short of the walls thereof, a plurality of fuel orifices adapted to discharge jets of fuel in the immediate lee of said projections transversely of the passage means and longitudinally of the projections toward the tips thereof, and a fuel conduit in said support for supplying fuel to said fuel orifices.

18. In a charge forming device, an induction passage, a finger like air shielding member having a substantially flat leeward surface and projecting transversely within the passage, said member having a tip end spaced from the wall of the passage, a fuel nozzle adapted to discharge a jet of fuel transversely of the passage from a point adjacent the face of the member in the lee of and longitudinally of the air shielding member toward the tip thereof, means for supplying fuel to said nozzle, an air discharge nozzle positioned adjacent the fuel nozzle to discharge a jet of air which intersects the jet of fuel discharged by the fuel nozzle to thereby break up the fuel being delivered in the lee of the member and to cooperate with the shielding member to control the distribution of fuel through the passage, and means for supplying air to the air discharge nozzle.

19. In a charge forming device, means defining an induction passage, a member having a plurality of finger-like projections extending transversely within and only partially across said passage, said projections being inclined from base to tip in the direction of air flow, a fuel discharge orifice adjacent the base of each projection arranged to discharge a jet of fuel substantially transversely of said induction passage in the lee of and toward the tip of said pro-

jection along a line which intersects the leeward side of said projection.

20. In a charge forming device, a body having an induction passage therethrough, a member supported on the body and having a plurality of finger-like projections extending therefrom transversely within the induction passage and terminating at points spaced from the induction passage wall, said projections having substantially flat leeward surfaces, and fuel discharge ports adapted to discharge jets of fuel transversely of the induction passage in the immediate lee of said projections and in a direction longitudinally of the projections toward the tips thereof.

21. In a charge forming device, a body, induction passage means extending through the body, a substantially "X"-shaped member supported adjacent its central portion on the body and having its arms projecting transversely of and only partially across the passage means, fuel discharge orifices adjacent the central portion of the "X" member in the lee of the bases of said arms and adapted to discharge jets of fuel transversely of the induction passage toward the ends of and in the immediate lee of said arms, and means for supplying fuel to said orifices.

22. In a charge forming device, a body, induction passage means extending through the body, a substantially "X"-shaped member supported adjacent its central portion on the body and having its arms extending transversely of the passage means, said arms being curved in both the longitudinal and transverse planes of the induction passage means and having substantially flat leeward surfaces, a fuel discharge nozzle adjacent the central portion of said "X" member, discharge orifices in the nozzle in the immediate lee of the bases of said arms and positioned to discharge jets of fuel transversely of the passage means in the lee of the arms, and a conduit for supplying fuel to said discharge orifices.

23. In a charge forming device, a pair of spaced parallel induction passages, a wall between the passages forming a support, a substantially X-shaped member mounted adjacent its central portion on the support and having two of its arms extending transversely within and only partially across each induction passage, said arms being curved in both the longitudinal and transverse planes of the induction passages and the tip of the arms being downstream from the base of the arms, a fuel orifice adjacent the base of and in the lee of each arm adapted to discharge a jet of fuel transversely of the passage in the lee of the arm along a line which intersects the leeward side of the arm.

FRANK C. MOCK.

CERTIFICATE OF CORRECTION.

Patent No. 2,372,332.

March 27, 1945.

FRANK C. MOCK.

It is hereby certified that error appears in the printed specification of the above numbered patent requiring correction as follows: Page 2, first column, line 32, for "conduit 39" read --conduit 30--; page 6, first column, line 39, claim 18, for "face" read --base--; line 56, claim 19, after the word and comma "flow," insert --and--; and that the said Letters Patent should be read with this correction therein that the same may conform to the record of the case in the Patent Office.

Signed and sealed this 12th day of March, A. D. 1946.

Leslie Frazer

(Seal)

First Assistant Commissioner of Patents.
